FIG. 1

FIG. 3

FIG. 1 is a perspective view of the front and one side of a combined mobile bar refrigerator and table showing my new design;

FIG. 2 is a perspective view thereof of the front and side shown in FIG. 1 with the refrigerator cover in its open condition; and

FIG. 3 is a perspective view thereof of the rear and side shown in FIG. 1.

The side opposite to that shown in the drawings is substantially a mirror image thereof.

The cover on the forward storage compartment shown in FIG. 3 has been omitted in FIGS. 1 and 2 for convenience of illustration.

I claim:

The ornamental design for a combined mobile bar refrigerator and table, as shown and described.
